(57) **CLAIM**

The ornamental design for a hand aerosol fire extinguisher, as shown and described.

DESCRIPTION

FIG. 1 is an upper perspective view of a first embodiment of a hand aerosol fire extinguisher in accordance with the present invention.

FIG. 2 is a lower perspective view of the hand aerosol fire extinguisher first embodiment shown in FIG. 1.

FIG. 3 is a bottom plan view of the first embodiment shown in FIG. 1.

FIG. 4 is a side elevational view of the first embodiment shown in FIG. 1.

FIG. 5 is a top plan view of the first embodiment shown in FIG. 1.

FIG. 6 is an upper perspective view of a second embodiment of the hand aerosol fire extinguisher shown in FIG. 1, the only difference being that the outlet openings are arranged on a planar surface in the upper hemisphere of the design, instead of being arranged in the top of the curved surface of the upper hemisphere itself as shown in FIG. 1, it being understood that all other surfaces are the same as those of the first embodiment.

FIG. 7 is a lower perspective view of the hand aerosol fire extinguisher second embodiment shown in FIG. 6.

FIG. 8 is a bottom plan view of the second embodiment shown in FIG. 6.

FIG. 9 is a side elevational view of the second embodiment shown in FIG. 6; and,

FIG. 10 is a top plan view of the second embodiment shown in FIG. 6.
